Design Re. 16,182

UNITED STATES PATENT OFFICE.

MOSES HIRAM HARRIS, OF NEW YORK, N. Y.

DESIGN FOR A SCREEN.

Original No. 65,186, dated July 15, 1924, Serial No. 459,168, filed April 6, 1921, for 3½ years. Application for reissue filed November 25, 1924. Serial No. 11,470. Term of patent 14 years.

To all whom it may concern:

Be it known that I, MOSES HIRAM HARRIS, a citizen of the United States, residing at New York city, in the county and State of New York, have invented a new, original, and ornamental Design for a Screen, of which the following is a specification, reference being had to the accompanying drawing, forming part thereof.

The figure is a front elevational view of a screen showing my new design.

I claim:

The ornamental design for a screen, as shown.

In testimony whereof I affix my signature.

MOSES HIRAM HARRIS.
